UNITED STATES PATENT OFFICE

GEORGE E. WHITMORE, SR., OF WILLIAMSON, WEST VIRGINIA

AUTOMATIC RAIL AND WHEEL-FLANGE OILER

Application filed March 18, 1926. Serial No. 95,726.

This invention relates to lubricating apparatus.

The principal object of the invention, generally stated, is to provide means whereby 5 the rail or rails of a railroad track and the flanges of wheels passing thereover may be supplied with lubricant.

The object of the invention, more specifically stated, is to provide means for applying 10 lubricant to a rail of a railroad track whereby the lubricant will be taken up by the flanges of wheels passing along the track and distributed thereby throughout a long extent of the track.

15 An important object of the invention is to provide a lubricating device which, if located at the outer rail near or at the beginning of a curve, will be capable of providing lubrication of many miles of rail on account 20 of the distributing action of car wheels passing along the track.

Another important object of the invention is to provide a device which will act automatically upon the passage of car wheels 25 thereover to apply lubricant directly to the inside of the ball of a rail so that the flanges of successive wheels passing along the track may take up the lubricant and distribute it throughout a long extent.

30 Another object of the invention is to provide a device of this character adapted to be carried directly by the rail to be lubricated.

A further object of the invention is the provision of a lubricating device which is 35 normally inactive and which will operate to apply lubricant to a rail only when the successive wheels of a train pass over the point where the apparatus is located, the device embodying an actuating element disposed 40 in the path of travel of the wheel flanges.

Still another object of the invention is to provide a rail lubricating device provided with or embodying a reservoir capable of containing sufficient lubricant for an extended period of time, the construction being, 45 moreover, such that water, dirt or other foreign matter will be excluded.

An additional object is to provide a device 50 of this character so constructed, arranged and shaped as not to be damaged or destroyed

in case it is struck against by a loose part of the brake rigging, or the like, hanging from a car or any part of a train passing along the track, the device being preferably so formed as to deflect any such elements. 55

A still more specific object of the invention is to provide a rail lubricating device embodying a movable actuating member de- 60 pressible by car wheels passing thereover and carrying a species of swab adapted to engage against the side of the rail ball, positive means being located within the device and operatively connected with said movable actuating element for supplying lubricant to the swab, means being also provided for normally maintaining all the parts in neutral or inoperative position and returning them to such after each actuation. 65

Yet another object of the invention is to provide a lubricating device of this character which will effect thorough lubrication of a rail regardless of the condition thereof, that is to say whether it be new or even badly worn, the device embodying means for adjusting the position of the swab or lubricant applying element with respect to the rail so as to obtain the best results under certain rail conditions. 70 75

To the attainment of the foregoing and other objects and advantages, the invention preferably consists in the detailed construction and the arrangement and combination of parts to be hereinafter more fully described and claimed, and illustrated in the accompanying drawings in which: 80 85

Figure 1 is a plan view of the device in applied position upon the rail of a track,

Figure 2 is a vertical cross sectional view taken on the line 2—2 of Figure 1,

Figure 3 is a vertical longitudinal section 90 taken on the line 3—3 of Figure 2 showing an elevation of the rail engaging side of the device, and

Figure 4 is a fragmentary detail perspective view illustrating the mounting of the dipper or member for supplying oil to the swab. 95

Referring more particularly to the drawings the letter A designates a railroad rail here represented as mounted upon a seat member B and spiked at C onto the cross ties 100 105

D. The rail is shown as tilted or canted inwardly in accordance with the modern practice which has been adopted for the purpose of having the wheel treads bear properly upon the rails. However, this is a detail which has no particular bearing on the present invention, the rail and associated parts being disclosed simply for the purpose of more clearly explaining the construction, 10 mounting and operation of the device forming the subject matter of the application.

In carrying out the invention I provide a suitable reservoir structure adapted to be mounted at some convenient location along 15 the trackway and adjacent the rail to be lubricated. For the sake of illustration, I have shown the reservoir structure formed as an elongated receptacle or pan 1 which may conveniently be formed of sheet metal and 20 which is preferably of a general trough shape including a bottom 2, sides 3 and 4 and an outstanding flange 5 at the top of the latter. If desired these elements may be formed integrally as by cutting and stamping or bending a sheet of metal though, obviously, there 25 is no limitation in this respect as various alternative arrangements might be provided if found advisable. This receptacle or reservoir structure may well be attached to the rail 30 to be lubricated, in which event the side 3 is disposed against the inner side of the web of the rail A and secured thereto as for instance by bolts 6 passing through the side 3, through the rail web and through washers, plates, 35 blocks or other filler elements indicated at 7, the bolts being equipped with nuts 8 for effecting the proper holding action. This pan or reservoir has its sides 3 and 4 preferably inclined downwardly at the ends as shown 40 at 9 and these end portions are covered by wall members 10 preferably formed with filling openings 11 normally covered by movably mounted plates or other equivalent closure elements 12.

45 The receptacle or pan is intended to be filled with lubricant to any desired depth, naturally less than the height of the side 3 to avoid spilling, and it is preferable that the bottom 2 be inclined downwardly from the 50 wall 4 toward the wall 3 for the purpose of causing the lubricant to gravitate toward the rail. While it is not essential, I have shown a support or supports 13 mounted upon the cross tie or ties D adjacent that portion of the 55 receptacle most remote from the rail for the purpose of supporting the reservoir or receptacle and preventing strain upon the wall member or side 3 and eliminating distortion. For convenience in installation the side wall 60 3 is represented as terminating short of the ball of the rail and it is of course necessary that the top members 10 at the inclined ends be arranged sufficiently low as to be out of the path of travel of the flanges of car wheels 65 passing along the track. The top of the

reservoir structure or receptacle is open between the inner edges of the inclined top wall members 10 for a purpose to be described. While it may not be of vital importance the wall member or side 4 extends upwardly to a point approximately in line with the top of the rail A and the flange 5 is preferably inclined downwardly away from the rail as indicated for a reason which will be herein-after made apparent.

75 The open top of the reservoir structure or receptacle is provided with a movably mounted closure or cover 14 suitably pivotally mounted as by hinges 15, or the like, located at the upper portion of the side wall 4, there being no restriction, however, as to the details of mounting. This cover has its free edge extending to a point adjacent the ball of the rail but sufficiently spaced therefrom to permit it to clear the rail when swung downwardly upon its pivot or pivots 15. Ordinarily the cover may preferably be arranged in a horizontal plane and substantially in line with the top of the rail, there being a space 16 between the flange 5 and that portion 80 of the cover overlying the same. Detachably mounted upon the cover at the free edge thereof is a swab member 17 of flexible material held in place by some suitable means such, for instance, as a clamping plate 18. For all practical purposes the swab member 17 may, if desired, consist of a length of ordinary rubber hose slit longitudinally and held between the cover and the clamp, though it should be distinctly understood that any 85 equivalent may be provided. When the cover 14 is in normal position it will be clear that the swab member 17 lies against the side of the ball of the rail and it can never get into such position as to touch the top of the rail.

90 100 105 110 115 120 125 130
Mounted on top of the free edge portion of the cover is a ramp 19 which is adapted to be engaged by the flanges of car wheels passing along the rail, the purpose being to move the cover 14 downwardly as successive car wheels pass thereover. The ramp is preferably highest at its central portion if the device is to be used on a two-way track though it might be well to mention that on a one-way track the highest portion of the ramp may be the end farthest from the direction from which trains approach the device. Obviously, the ramp 19 should extend to such a height that when engaged by the flanges of car wheels the result will be that the cover 14 will swing downwardly upon its pivot or pivots 15. While any desired means may be provided for securing the ramp in place, I have illustrated bolts 20 which also serve to hold the clamping plate 18 in position, the bolts having their heads preferably located within recesses 21 in the ramp in such position as to be easily capable of engagement by a suitable socket wrench for effecting loosening of the clamping plate 18 whereby a new swab 17 may be

inserted, when necessary. It is preferable that the upper surface of the ramp be inclined or curved downwardly away from the rail and that the edge nearest the rail be curved upwardly and away from the rail, the latter feature being to provide clearance when the cover swings downwardly and the first mentioned feature being for the purpose of reducing likelihood of any depending brake rigging catching and causing damage. The same scheme for preventing destruction of the device by any element hanging from a train is carried out in connection with the receptacle and the cover therefor, the wall members 10 being inclined for this purpose and the corners of the flange 5 and the overlying portion of the cover being beveled or inclined at 22. These details are refinements in the structure and I do not wish to be restricted thereto.

20 The invention contemplates means for positively applying lubricant to the swab 17 every time the cover 14 swings downwardly. To accomplish this I preferably provide a dipper 23 which may in actual practice be formed 25 simply as a plate with an upwardly curved end 24. This dipper is suitably pivoted within the receptacle in such manner as to have a somewhat scooping movement. The mounting in the present instance is represented as 30 including any desired number of upright bearings 25 rising from the bottom 2 and journally receiving a rod or shaft 26 secured to the dipper in any desired manner. The scooping movement may be insured by providing the dipper with openings 27 which receive the bearing members 25. By locating the dipper beneath the shaft or rod 26 it is evident that the dipper will have the desired movement when swung. The operative connection 35 between the cover and the dipper may consist of any desired number of ears 28 and 29 carried, respectively, by the dipper and the underside of the cover and pivotally connected at 30 with a corresponding number of links 31. While ears are mentioned, it should be understood that any equivalent elements may be employed to equal advantage and the same may be said of the links.

For maintaining the cover and the other parts in normal position and restoring them to such after movement by the passage of car wheels over the ramp, I preferably provide bolts or guide rods 32 passing through the flange 5 and the overlying portion of the cover, these elements 32 carrying abutment members 33 against which engage coil springs 34 which, in turn, abut against washers 35 or the like beneath the flange 5. Obviously, any equivalent spring means may be provided in lieu of this detailed construction. It is desirable to provide an adjustment for the spring tension and this is readily accomplished by means of nuts 36 on the bolts beneath the abutment members thereon.

65 It is of particular advantage to be able to

adjust the position of the cover 14 so as to bring the swab 17 into proper relation to the rail, especially in case the rail is worn to a greater or less extent, and for this reason I have shown set screws 37 passing through the flange 5 and engaging beneath the overlying portion of the cover. These screws constitute stops for limiting the return movement of the cover under the influence of the springs provided for the purpose and it is clear that by adjusting these set screws the free edge of the cover may be brought into position above, in line with, or below the top of the rail, as the case may be, depending upon circumstances and conditions which may exist.

In the operation, it will be seen that the first step is to fill the reservoir with lubricant to the desired level. The normal position of the parts is as shown by full lines in Figure 2. Attention is directed to the fact that at this time the cover 14 is in horizontal position with the swab member 17 bearing against the side of the rail. The cover consequently forms a closure for the open top of the receptacle so that water and dirt or other foreign matter will be excluded. The dipper 23 is in inclined position with its curved end 24 lowermost and dipping down into the lubricant. Upon the approach 5 of a train and the passage of the wheels over the rail where the device is located, the wheel flanges will successively engage the ramp 19, forcing it, and consequently the cover 14, downwardly against the resistance of the springs 34. As the cover swings downwardly the links 31 connecting the elements 29 and 28 will cause the dipper 23 to swing upon its pivot. The parts are so related and the movement so timed that as the curved end 24 of the dipper swings upwardly it is met by and receives the swab member 17 which, being flexible, follows around the curve at the concave side of the dipper end. This position is shown by dotted lines in 10 Figure 2. Lubricant is thus effectually applied to the swab. As soon as pressure of a wheel flange upon the ramp is relieved, the springs 34 operate to return the cover to its uppermost position, the swab 17 then re-engaging against the side of the rail and transferring the lubricant thereto. Of course the dipper and other parts likewise return to normal or initial position. As successive wheels pass over the device the 15 flanges thereof will take up the lubricant applied to the rail by the swab at the preceding stroke or movement of the device and will distribute the lubricant along the rail for a great extent. In actual practice I have discovered that if one of the devices be located at the beginning of a curve and of course at the outside rail thereof it will operate to lubricate as much as twenty miles of track. In the case of compound curves 20

it is probably preferable to provide one of the devices at the beginning of the outside rail of the different curves. However, as many of the devices may be used as may be found advisable and they may be located at any points desired, this being principally a matter of judgment and depending, of course, upon track conditions. I have also found that a badly worn rail may be lubricated just as effectually as one in good condition.

From the foregoing description and a study of the drawings it will be apparent that I have thus provided a simply constructed, inexpensive and easily installed device for the purpose specified and one which will positively accomplish all the beneficial results contemplated. The device should need no attention other than replenishment of the lubricant supply from time to time. Attention might be directed to the fact that owing to the inclination of the bottom toward the rail the device will operate even though it contains an extremely limited supply of lubricant. The action is automatic and as the parts are rugged the device should possess great durability especially as the dimensions and shape of the ramp may be so designed or calculated as to insure proper depression of the cover and consequent operation of the parts without undue shock or strain caused by wheel pressure at high speeds. Such details are matters of engineering skill and do not affect the principles involved.

While I have shown and described a preferred embodiment of the invention, it should be understood that the disclosure is merely an exemplification of the possibilities as I reserve the right to make all such changes and modifications as will increase the field of utility and adaptability of the invention, provided such variations constitute no departure from the spirit of the invention or the scope of the claims hereunto appended.

Having thus described the invention, I claim:

1. Means for lubricating a railroad rail and consequently the flanges of wheels passing therewith, including a lubricant receptacle positioned adjacent the rail to be lubricated, a member movably mounted with respect to the reservoir and compressible by the flanges of wheels passing along the rail, swab means carried by said movable member normally engaging the side of the rail, and means movably mounted within the receptacle and operatively connected with said movable member for applying lubricant to the swab means.

2. Means for lubricating a rail and the flanges of wheels passing thereover, comprising a reservoir structure adapted to be mounted adjacent the rail to be lubricated

and containing lubricant, a pivotally mounted member on said reservoir structure located in the path of movement of car wheels passing along the rail and movable thereby, means on said movable member engageable against the rail, and means operatively connected with said pivot member for applying a charge of lubricant to said means.

3. In a rail and wheel flange lubricator, a receptacle adapted to be mounted at a rail to be lubricated and adapted to contain lubricant, a movably mounted closure for the receptacle disposed in the path of travel of the flanges of car wheels passing over the rail, means carried by the closure engageable with the side of the ball of the rail, and means for applying lubricant to said means.

4. In a rail and wheel flange lubricator, a receptacle adapted to be mounted at a rail to be lubricated and adapted to contain lubricant, a movably mounted closure for the receptacle disposed in the path of travel of the flanges of car wheels passing over the rail, means carried by the closure engageable with the side of the ball of the rail, and means for applying lubricant to said means, the last named means including a movably mounted mechanism dipping into the receptacle and engageable with the first named means upon downward movement of the closure.

5. In a rail lubricator, a receptacle adapted to be secured to the web of a rail to be lubricated, a pivoted closure for the receptacle positioned in the path of travel of the flanges of car wheels passing over the rail, a dipper structure movably mounted within the receptacle, the receptacle being adapted to contain lubricant into which the dipper normally extends, swab means on the closure engageable with the rail, and an operative connection between the closure and the dipper for bringing the dipper and swab means into engagement upon depression of the closure.

6. In a rail lubricating device, a stationary reservoir structure adapted to be mounted adjacent a rail to be lubricated and adapted to contain lubricant, a movably mounted member extending inwardly of the rail at substantially right angles thereto and positioned in the path of travel of car wheels passing along the rail and movable thereby, means carried by said movable member normally contacting the rail, and movable means for applying lubricant to said means.

7. In a rail lubricating device, a reservoir structure adapted to be mounted adjacent a rail to be lubricated and adapted to contain lubricant, a movably mounted member positioned in the path of travel of car wheels passing along the rail and movable thereby, flexible means carried by said movable member normally contacting the rail, and means for applying lubricant to said flexible means,

- said last named means including a member dipping into the lubricant and operatively connected with said movable member to be moved into engagement with said flexible means.
8. In a rail lubricator, a lubricant receptacle adapted to be mounted along a track-way adjacent a rail to be lubricated, a pivoted closure for the receptacle carrying a ramp positioned in the path of travel of car wheels passing along the rail, a pivoted dipper within the receptacle extending normally into the lubricant, and means connecting the pivoted closure with the dipper for effecting simultaneous movement thereof.
9. In a rail lubricator, a lubricant receptacle adapted to be mounted along a track-way adjacent a rail to be lubricated, a pivoted closure for the receptacle carrying a ramp positioned in the path of travel of car wheels passing along the rail, a pivoted dipper within the receptacle extending normally into the lubricant, means connecting the pivoted closure with the dipper for effecting simultaneous movement thereof, and swab means on the closure normally contacting the rail and engageable by the dipper upon downward movement of the closure.
10. In a rail lubricator, a stationarily mounted lubricant receptacle, a movably mounted member on the receptacle carrying a swab engageable with the rail, said movable member being positioned in the path of travel of car wheels passing along the rail and movable thereby, means for applying lubricant to the swab upon movement of the movable member in one direction, and screw means for varying the initial position of the movable member and swab with respect to the top of the rail.
11. In a rail lubricator, a receptacle adapted to be mounted adjacent a rail to be lubricated, said receptacle having the central portion of its top open and having its end portions extended downwardly out of obstructing relation to the flanges of car wheels passing along the rail, said receptacle being adapted to contain a lubricant, a hinged closure plate normally covering the open top of the receptacle and carrying a ramp located in the path of travel of the flanges of wheels passing along the rail, means carried by said closure plate normally engaging against the inner side of the rail, and means for applying lubricant to said means.
12. In a rail lubricator, a receptacle adapted to be mounted adjacent a rail to be lubricated, said receptacle having the central portion of its top open and having its end portions extended downwardly out of obstructing relation to the flanges of car wheels passing along the rail, said receptacle being adapted to contain a lubricant, a hinged closure plate normally covering the open top of the receptacle and carrying a ramp located in the
- path of travel of the flanges of wheels passing along the rail, means carried by said closure plate normally engaging against the inner side of the rail, and means for applying lubricant to said means, said closure plate projecting beyond the side of the reservoir most remote from the rail to define an extension, spring means located beneath said extension for normally maintaining the closure plate in its uppermost position.
13. In a rail lubricator, a receptacle adapted to be mounted adjacent a rail to be lubricated, said receptacle having the central portion of its top open and having its end portions extended downwardly out of obstructing relation to the flanges of car wheels passing along the rail, said receptacle being adapted to contain a lubricant, a hinged closure plate normally covering the open top of the receptacle and carrying a ramp located in the path of travel of the flanges of wheels passing along the rail, means carried by said closure plate normally engaging against the inner side of the rail, means for applying lubricant to said means, said closure plate projecting beyond the side of the reservoir most remote from the rail to define an extension, spring means located beneath said extension for normally maintaining the closure plate in its uppermost position.
14. A rail lubricator comprising a receptacle adapted to be mounted adjacent a rail to be lubricated, the receptacle being adapted to contain lubricant, a movable closure for the top of the receptacle, means on the closure disposed in the path of travel of the flanges of car wheels passing along the rail whereby the closure will be moved, means carried by the closure and adapted to contact with the side of the ball of the rail, and means operating upon movement of the closure for applying lubricant to said last named means.
15. A rail lubricator comprising a lubricant receptacle adapted to be mounted adjacent a rail to be lubricated, a movable closure for the top of the receptacle, and means carried by the closure and movable downwardly upon passage of car wheels along the rail whereby to receive a charge of lubricant and transfer the same to the ball of the rail upon subsequent upward movement.
16. A rail lubricating device comprising a receptacle adapted to be mounted adjacent a rail to be lubricated and adapted to contain lubricant, means movably mounted at the top of the receptacle and carrying means located in the path of travel of the flanges of car wheels passing along the rail and depressible thereby, means carried by said second named means adapted to contact with the side of the ball of the rail, and means operable upon downward movement of said first named

means for elevating a charge of lubricant to said last named means.

17. A rail and wheel flange lubricating device comprising a lubricant receptacle having a depressible cover provided with means engageable by passing car wheels, and means actuated by movement of said cover for transferring lubricant from the receptacle to the rail.

18. A rail and wheel flange lubricating device comprising a receptacle for lubricant, a depressible top closure for the receptacle adapted to move up and down upon passage of car wheels along the rail, a rail contacting applicator on said top closure and means within the receptacle for elevating lubricant therein to the applicator upon each up and down movement.

19. A rail and wheel flange lubricating device comprising a receptacle for lubricant, depressible means at the top of the receptacle carrying a ramp engageable by passing car wheels and movable thereby, and means within the receptacle and normally dipping into the lubricant and operable upon movement of said depressible means for transferring lubricant from the receptacle to the rail.

20. In an apparatus for lubricating a rail and the flanges of car wheels passing thereover, a reservoir adapted to contain lubricant, a member carrying a lubricant applicator adapted to be moved into and out of engagement with the side of the rail, said member having a portion extending in the path of travel of the car wheels and depressible thereby, and means operated by movement of said member for transferring lubricant from the reservoir onto said applicator.

In testimony whereof I affix my signature.
